UNITED STATES PATENT OFFICE.

IKE SCHLESINGER, OF EAST ORANGE, NEW JERSEY, ASSIGNOR TO ABNER M. COHEN AND JENNIE B. COHEN, TRADING AS ESSEX KNITTING MILLS, OF NEWARK, NEW JERSEY.

KNITTED CAP.

Application filed November 25, 1925. Serial No. 71,385.

This invention relates to knitted caps. Among the objects of the invention is the provision of a cap of the character described of general improved construction which is 5 neat in appearance, adapted to be fashioned into various desirable styles, strong, durable, comprises few and simple parts, easy and cheap to manufacture, and practical and efficient to a high degree.

10 Other objects of this invention will in part be obvious and in part hereinafter pointed out.

The invention accordingly consists in the features of construction, combinations of 15 elements, and arrangement of parts which will be exemplified in the construction hereinafter described, and of which the scope of application will be indicated in the following claims.

20 In the accompanying drawing, in which is shown one of the various possible illustrative embodiments of this invention,

Fig. 1 is a perspective view showing a 25 knitted cap embodying the invention in position on the wearer's head with the rear band unfolded and secured beneath the chin of the wearer;

Fig. 2 is a perspective view of the cap showing the rear band positioned about the 30 crown portion;

Fig. 3 is a perspective view showing the crown, foldable rear band and front band of the cap separated from each other; and

35 Fig. 4 is a cross-sectional view of the crown of the cap taken on line 4—4 in Fig. 3.

Referring in detail to the drawing, 10 denotes a knitted cap embodying the invention which is seen to comprise a crown 11, a rear band 12 and a front band 13, said bands 12 and 13 being fastened to the rim of the crown along suitable seams 14 and 15 respectively, as shown in Fig. 2.

The crown 11 is preferably made of a 45 single, tubular knitted piece, folded on itself into a double thickness forming an outer layer 11^a and an inner or lining layer 11^b. The top 11^c of said crown may be arculate shape and provided with a suitable 50 closure seam 16 for joining the free ends of said layers at the crown top 11^c to conform the latter to the contour of the wearer's head. If desired, the crown may be made of material that is capable of having a brushed 55 surface formed thereon, in the well under-

stood manner, such brushed surface being preferably provided on the lining layer 11^b facing the head opening crown as shown in Figs. 2 and 4.

The rear band 12 is seen to comprise a 60 rectangular shaped, middle section 12^a having flaps 12^b extending in angular relation with respect thereto from each end thereof. Said section 12^a and ends flaps 12^b preferably are knitted to form the band 12 as a 65 single, continuous piece, said band being so made that when the section 12^a is attached to the crown 11 along the seam 14 and lies against the latter, the flaps extend upwardly and forwardly and serve as a neat trimming 70 for the cap. The band 12 when folded down to cover the back of the neck of the wearer makes said flaps 12^b available for use as chin straps as shown in Fig. 1. For releasably retaining the band either in its up- 75 folded or downfolded position as shown in Figs. 1 and 2, suitable quick detachable fastening means are provided, as for example a button hole 12^c in each of the flaps 12^b for engaging with buttons 18 attached to the 80 crown 11 and a button 19 secured on the rear side of one of the flaps 12. To give a pleasing contrasting trimming effect to the cap, the band section 12^a may be knitted with one style of stitch such as the half 85 cartigan on the outer side thereof, and the flaps with a different style such as the jersey rib stitch. Whatever types of stitches may be selected for knitting said band, the stitch 90 preferably employed for the inner side thereof should be such as to provide rows of continuous ribs extending from the end of one flap to the end of the other flap throughout the band as shown in Figs. 1 and 3. The band thus constructed is capable of 95 withstanding severe strains due to rough usage and handling to which a knitted cap of this type is generally subjected.

The front band 13 may be knitted of any 100 desired style of stitch to blend or contrast in appearance with the stitches of the crown and rear band 12, said band 13 being preferably secured in an upfolded position against the crown by tacking the ends of the band to the crown as at 20.

A short row of anchoring stitches 21 may be passed through each of the lower corners of the band section 12^b and the crown 11 for reinforcing the adjacent portion of the seam 14 as shown in Fig. 2.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

A cap of the character described comprising a single tubular piece, rib-knitted length-

wise thereof and folded on itself to form a crown having inner and outer layers, the bight portion of the folded piece forming the rim of the head opening of the crown, and an integrally knitted band having longitudinally extending ribs throughout its entire length, said band comprising a substantially rectangular shaped central portion and end portions extending in angular relation to the rectangular portion, one side edge of said central portion being attached to the rim, the end portions forming flaps adapted for detachable attachment with the crown, or with each other beneath the chin of the wearer.

In testimony whereof I affix my signature
IKE SCHLESINGER.
